POLISHING MACHINE

Webster B. Knight, Detroit, Mich.

Application April 5, 1950, Serial No. 154,034

15 Claims. (Cl. 51—76)

1

The present invention relates to a polishing machine for polishing the heads of screws or other similar workpieces.

This invention relates to an improved polishing machine of the type illustrated, described and claimed in my copending application, Serial No. 55,585, filed October 20, 1948.

It is an object of the present invention to provide an improved polishing machine of the above mentioned type, including an improved hopper into which the screws to be polished are loaded, an improved conveyor means for supporting the screws during the polishing operation, improved means for transferring the screws from the hopper to the conveyor means, and improved means for polishing the heads of the screws as they are carried along the conveyor means, all of which co-operate to form a polishing machine which more rapidly collects the screws to be polished, permits improved polishing of the workpieces, and greatly increases the production of the machine.

Another object of the present invention is to provide an improved polishing machine of the above mentioned type in which the conveyor means includes means for rotating the screws about their axes during the polishing operation, to insure complete polishing of the entire screw head.

Another object of the invention is to provide an improved hopper for a polishing machine of the above mentioned type, which hopper includes an annular axially upwardly opening slot and baffles engaging the screws disposed within the hopper causing these screws to fall across the slot to facilitate the collection of the screws within the slot.

It is also an object of the present invention to provide an improved means for handling screws or other similar workpieces including an improved conveyor for supporting the screws during the polishing operation, a slide for delivering the screws to the conveyor, and improved transfer means for transferring the screws from the slide to the conveyor.

It is also an object of the present invention to provide improved polishing means for a polishing machine of the above mentioned type, which polishing means includes polishing wheels and improved means for supporting the polishing wheels so the wheels may be adjusted toward and away from the conveyor means and so that the wheels may also be adjusted to vary the angle between the plane of the wheels and the path of movement of the screws along the conveyor.

2

Another object of the invention is to provide an improved polishing machine providing greatly increased production and which is very versatile in that it may be readily adapted to handle various sizes of workpieces.

A further object of the invention is to provide an improved polishing machine of the above mentioned type which is of sturdy, durable construction and which is reliable and efficient in operation.

Other and more detailed objects of the invention will be apparent from the consideration of the following specification, the appended claims and the accompanying drawings, throughout the several views of which like reference characters designate like parts and wherein:

Figure 1 is a broken elevational view of a polishing machine embodying the present invention;

Figure 1A is a broken enlarged sectional view 20 of the structure illustrated in Figure 1 taken along the line 1A—1A thereof;

Figure 2 is an enlarged broken longitudinal sectional view showing the left hand portion of the structure illustrated in Figure 1;

Figure 3 is an enlarged sectional view of the structure illustrated in Figure 2, taken substantially along the line 3—3 thereof;

Figure 4 is a broken sectional view of the structure illustrated in Figure 2, taken substantially along the line 4—4 thereof;

Figure 5 is a broken plan view of the structure illustrated in Figure 2, taken in the direction of the arrow 5 therein;

Figure 6 is a broken sectional view of the structure illustrated in Figure 5, taken substantially along the line 6—6 thereof;

Figure 7 is a broken perspective view of the structure illustrated in Figure 2;

Figure 8 is a sectional view of the structure illustrated in Figure 5, taken substantially along the line 8—8 thereof;

Figure 9 is an enlarged sectional view of the structure illustrated in Figure 5, taken substantially along the line 9—9 thereof;

Figure 10 is a sectional view of the structure illustrated in Figure 1, taken substantially from the line 10—10 thereof; and,

Figure 11 is a broken sectional view of the structure illustrated in Figure 1, taken substantially along the line 11—11 thereof.

The improved polishing machine of the present invention generally comprises a fabricated main frame generally indicated at 20, a hopper 22 supported on a suitable frame 24, a conveyor generally indicated at 26 mounted on the frame 20

and adapted to support the screws and convey them along in position for the heads to be polished, pickup and transfer means generally indicated at 28 adapted to remove the screws from the hopper 22 and transfer them to the conveyor means 26, a plurality of polishing means generally indicated at 30 supported on the frame 20 and adapted to polish the heads of the screws as they are carried along the conveyor 26, and driving means for driving the conveyor 26, the polishing means 30 and the hopper 22.

Considering the above mentioned components in greater detail, the hopper 22 is formed of metal and has a conically shaped side wall 34 which is disposed on an inclined axis as best illustrated in Figures 1, 2 and 7. At its inner and smaller diameter, the conical wall 34 carries an annular bottom ring 36 welded or otherwise suitably secured thereto. Within the opening defined by the annular ring 36, a bottom plate 38 is supported on a plurality of C-shaped brackets 40. The plate 38 co-operates with the annular ring 36 to define an annular slot 42. Adjacent the slot 42, the upper surfaces of the ring 36 and plate 38 are formed to define annular recesses in which are supported annular rings 44 and 46 respectively, which are secured in place by a plurality of screws 48 and 50. The annular rings 44 and 46 cooperate to define an annular slot 52 aligned with the larger slot 42 defined by the ring 36 and plate 38. It will be appreciated that the size of the slot 52 may be varied to correspond to the size of the screw being run on the machine and provide maximum collection of the screws in the slot 52 by replacing either or both of the annular rings 44 and 46.

A plurality of angularly spaced baffles 54 are mounted on the inner surface of the conical wall 34 and secured thereto by screws 56. The baffles 54 are inclined relative to the straight-line elements of the conical wall 34 so that the lower or axially inner ends of the baffles 54 trail the outer ends of the baffles during rotation of the hopper, which in the construction illustrated, is in the clockwise direction indicated by the arrow in Figure 4. The baffles 54 terminate at their inner ends adjacent the bottom ring 36 of the hopper and function to carry screws disposed in the hopper 22 upwardly during rotation of the hopper 22 in the direction indicated, causing them to fall downwardly toward the slot 52, thereby facilitating collection of screws in the slot 52.

An annular collar 58 is welded to the outer side of the conical wall 34 adjacent its lower or inner end and has a cylindrical outer surface 60 having a pair of pulley grooves which receive V-belts 62 for rotating the hopper 22 about its inclined axis. The hopper is rotatably supported on the frame 24 by a plurality of rollers 64 suitably supported on the frame 24 and adapted to engage the cylindrical outer surface 60 of the collar 58, and other rollers 66 also mounted on the frame 24 and engaging a bottom surface 68 of the collar 58, which bottom surface 68 is disposed at right angles to the cylindrical surface 60. The pulley belts 62 are trained over a drive pulley 70 supported on the frame 24 in laterally spaced relation to the hopper 22 in parallel relation thereto and drivingly connected to a suitable electric motor 72.

The pickup and transfer means 28 mentioned above includes a pair of generally parallel flat strips 74 which are interconnected at spaced intervals therealong by L-shaped elements 76 and

78 clamped together by bolts 80. These connecting elements support the strips 74 in parallel spaced relation to define a longitudinally extending slot 82 therebetween adapted to receive the shanks of the screws, the heads of which engage and are supported upon the upper edges of the strips 74. These strips 74 define an inclined slide along which the screws are transferred from the hopper 22 to the conveyor 26. At their upper ends the strips 74 are shaped to define finger 84 adapted to ride on the upper surface of the annular rings 44 and 46 at opposite sides of the slot 52 and remove from the slot 52 the screws which have collected therein and are carried to the fingers 84 by the rotation of the hopper 22. These fingers 84 function as described in greater detail in my copending application, Serial No. 55,585, filed October 20, 1948, to efficiently remove the screws which collect in the slot 52 and transfer them to the slot defined by the strips 74 where they slide along the strips 74 with their heads supported on the upper edge of the strips 74. The upper ends of the strips 74 are supported on a suitable framework generally indicated at 86 to dispose the fingers 84 in the above described relation to the slot 52. The framework 86 is suitably supported on the hopper frame 24, as by supporting elements 87 secured to the hopper frame 24 (see Figure 7).

As clearly illustrated in the drawings, the strips 74 slope downwardly from the fingers 84 at their upper ends toward the conveyor 26. To facilitate rapid travel of the screws downwardly along the strips 74, a pair of pneumatic vibrators 88 are secured to the frame 86. These vibrators 88 produce a vibration of the strips 74, resulting in rapid movement of the screws downwardly toward the conveyor 26. At the lower end of the strips 74, the screws are transferred to the conveyor 26, as hereinafter described.

The spacing of the strips 74 may be such as to accommodate a wide range of screw sizes since it need only be small enough to prevent the screw heads from falling between the strips 74 and great enough to be slightly more than the shank diameter of the screws. If necessary, of course, means may be provided on the elements 76 and 78 for clamping the strips 74 in various spaced relations.

The above mentioned conveyor means 26 comprise a pair of laterally spaced conveyor belts 90 and 92. These belts 90 and 92 are conventional endless V-shaped pulley belts and define generally horizontally extending loops, portions of which extend in spaced parallel relation to define a slot therebetween adapted to receive the shanks of screws carried by the conveyor. The main portion of the conveyor 26 is mounted on a horizontally disposed plate 94 supported on the main frame 20 and extending longitudinally thereof. At the right hand end of the plate 94, as viewed in Figure 1, and which is seen on an enlarged scale in Figure 11, a pair of coaxial shafts 96 and 98 are mounted in spaced pairs of bearing blocks 100 and 102 respectively. Pulley wheels 104 and 106 are secured to the adjacent ends of the shafts 96 and 98 respectively. The conveyor belts 90 and 92 are trained over the pulley wheels 104 and 106 respectively. At the opposite or left hand end of the main frame 20, as viewed in Figure 1, a pair of plates 108 and 110 are independently mounted on the main frame 20 in the plane of the plate 94, for movement toward and away from the plate 94.

The plates 108 and 110 carry coaxial shafts 120

and 122 rotatably supported thereon in pairs of bearing members 124 and 126 respectively. Referring to Fig. 2, the bearing members 124 are secured by bolts 123 to supports 125 welded or otherwise secured to the plate 108. Movement of the plate 108 toward and away from the plate 94 is effected by rotation of a handwheel 112 through a screw 114, which engages in a threaded boss 116 on one of the supports 125. Movement of the plate 110 toward and away from the plate 94 is similarly effected by a handwheel 118. Pulley wheels 128 and 130 are fixed on the adjacent inner ends of the shafts 120 and 122. The conveyor belts 90 and 92 are trained over the pulley wheels 128 and 130 respectively. It will be appreciated from the foregoing description that the tension in the conveyor belts 90 and 92 may be independently adjusted by rotation of the handwheels 112 and 118.

The conveyor belts 90 and 92 are driven through conveyor drive means generally indicated at 132 and comprising a motor 134 mounted in the lower right hand portion of the main frame 20, as viewed in Figure 1, the output shaft 136 of which carries a drive pulley 138 connected by a belt 140 to a large pulley 142 on an idler shaft 144. The idler shaft 144 also carries a small sprocket wheel 146 which is connected by a chain 148 to a large sprocket wheel 150 on a second idler shaft 152. The idler shaft 152 carries small drive sprocket wheels 154 and 156 which drive the shafts 96 and 98 respectively through chains 158 and 160 trained over sprocket wheels 162 and 164 mounted respectively on the shafts 96 and 98. It will now be appreciated that properly varying the sizes of the sprocket wheels 154 and 156 or 162 and 164, the relative speed of the conveyor belts 90 and 92 may be varied to produce any desired amount of rotation of the screws as they are carried along by the belts 90 and 92. It has also been found that rotation of the screws may be obtained when the sprocket sizes are the same by adjusting one of the handwheels 112 and 118 to produce a partial slippage of one of the conveyor belts.

To provide an effective uniform drive of the conveyor belts 90 and 92, under heavy load conditions the shaft 96, at the right hand end of the conveyor, is connected to the shaft 120 in the left hand end thereof by a double pulley belt 166 trained over pulley wheels 168 and 170 fixed on the shafts 96 and 120 respectively, and the shaft 98 is similarly connected to the shaft 122 by pulley belts 172 trained over pulley wheels 174 and 176 fixed on the shafts 98 and 122. Under light load conditions the belts 90 and 92 may transmit their own driving force completely and the belts 166 and 172 may be dispensed with.

A pair of longitudinally extending backup members 186 and 188 carry outwardly extending legs 187 and 189 welded or otherwise suitably secured thereto and having elongated slots 191 and 193 through which extend bolts 190 and 192 which engage in tapped holes in supporting blocks 182 and 184 spaced longitudinally of the plate 94 and welded or otherwise suitably secured thereto. It will be readily appreciated that this construction permits the backup members 186 and 188 to be adjusted relative to each other to vary the spacing therebetween.

These backup members 186 and 188 extend in spaced parallel relation and have recesses 194 and 196 respectively formed in the upper portion of their adjacent surfaces. These recesses 194 and 196 are shaped to receive the pulley belts 90 and

92 and support them with their adjacent faces disposed in spaced parallel relation as best illustrated in Figures 6 and 8. The belts 90 and 92 are held against movement upwardly out of the recesses 194 and 196 by plates 198 and 200 secured to the upper surfaces of the backup members 186 and 188 by bolts 202 and 204. The upper surfaces of the backup members 186 and 188 are inclined downwardly toward their outer edges and the adjacent portions of the cover plates 198 and 200 taper to thin sharp edges 206 and 208 spaced apart sufficiently to prevent interference with the heads of the screws during movement thereof along the conveyor 26. At the left hand end of the conveyor 26, as viewed in Figure 1, and which is shown on an enlarged scale in Figure 5, supports 178 and 180 are provided on the backup members 186 and 188, which carry spaced rollers 210 and 212 supported for rotation about vertical pivot pins 214 and 216 extending through the supports 178 and 180 and receiving nuts 215 and 217 on threaded lower end portions thereof. These rollers 210 and 212 have annular grooves 218 and 220 respectively, adapted to respectively engage the conveyor belts 90 and 92 intermediate the flywheels 128 and 130 and the backup members 186 and 188, and turn the belts to the above described position in which the adjacent faces thereof are disposed in the proper spaced parallel relation which is maintained by the backup members 186 and 188.

To the left of the rollers 210 and 212, as viewed in Figure 5, the supports 178 and 180 carry supporting blocks 230 and 232 welded to the upper surface thereof. These blocks 230 and 232 carry plates 234 and 236 which are horizontally disposed and have finger portions 238 and 240 respectively, which project between the rollers 210 and 212 and are disposed in engagement with the upper surface of the conveyor belts 90 and 92. As best illustrated in Figure 8, the thickness of these fingers 238 and 240 progressively decreases from their outer edges to their adjacent inner edges. Also, the thickness of the fingers 238 and 240 progressively decreases from the left to the right, as viewed in Figure 5. Brackets 242 and 244 overlie a portion of the plates 234 and 236 and these brackets 242 and 244 and the plates 234 and 236 are secured to the supporting blocks 230 and 232 by suitable screws 246 and 248. At their adjacent edges, the brackets 242 and 244 have vertically disposed flanges 250 and 252 between which are received the lower ends of the slide strips 74. These slide strips 74 are secured to the brackets 242 and 244 by screws 254 and 256, and, as best illustrated in Figure 9, terminate above the belts 90 and 92, thereby avoiding any interference therewith.

It will be appreciated that screws sliding down the slide strips 74 are transferred from the lower end thereof to the plates 234 and 236, from which they are picked up by the engagement of the conveyor belts 90 and 92 with the shanks of the screws as the belts 90 and 92 converge from the pulley wheels 128 and 130 toward the rollers 210 and 212. The formation of the plates 234 and 236 with the fingers 238 and 240, as above described, facilitates the transfer of the screws from the slide strip 74 to the conveyor belts 90 and 92.

At the right hand end of the conveyor mechanism 26, as viewed in Figure 1, and which is shown on a larger scale in Figure 11, the backup members 186 and 188 have supports 260 and 262 which are integrally formed thereon or suitably

secured thereto and upon which are mounted rollers 264 and 266 similar to the above described rollers 240 and 242 and which similarly support the conveyor belts 90 and 92 disposed with the adjacent faces thereof in spaced parallel relation. It will be noted that the pulley wheels 104 and 106 are spaced apart so that in moving to these pulley wheels from the rollers 264 and 266, the conveyor belts 90 and 92 diverge. Accordingly, just beyond or to the right, as viewed in Figure 11, of the rollers 264 and 266, the screws are dropped from the conveyor belts 90 and 92. In the construction illustrated in the drawings, a slide 268, suitably supported on the frame 20 of the polishing machine, is disposed to receive the screws falling from the conveyor belts 90 and 92 and convey the screws to a suitable receptacle (not shown).

During the travel of the screws along the conveyor 26, the heads of the screws are polished by the polishing means generally indicated at 30. Any desired number of the above mentioned polishing means 30 may be employed. In the construction illustrated in the drawings, five such polishing means 30 are employed and since they are all similar, only one will be described in detail herein. Referring to Figures 1, 10 and 11, the polishing means 30 are supported on a top plate 270 mounted on the frame 20. Each of the polishing means 30 includes a plate 272 supported on the upper surface of the plate 270 in contact therewith and having a cylindrical boss 274 welded or otherwise suitably secured thereto and depending therefrom. The boss 274 extends through an aperture 276 in the plate 270 and provides a pivotal connection permitting pivotal movement of the plate 272 relative to the plate 270. A motor 278 is mounted on the upper surface of the plate 272 and secured thereto by a plurality of bolts 280, one of which extends through an arcuately extending slot formed in the plate 270 (not shown) and carries a nut on its lower end for locking the plate 272 in adjusted pivotal position relative to the plate 270. Each polishing means 30 also includes a polishing wheel 282 fixed on one end of a horizontally disposed shaft 284 journaled in a movable bearing block 286 and which carries a pulley wheel 288 fixed to its other end. The bearing block 286 is supported on the cylindrical boss 274 of the plate 272 by a pair of oppositely threaded shafts 290 and 292 which are carried by the bearing block 286 and the boss 274 respectively and interconnected by a turnbuckle 294. The pulley wheel 288 and hence the polishing wheel 282, both of which are secured to the shaft 284, is driven by belts 296 trained over the wheel 288 and also trained over a pulley wheel 298 mounted on one end of a shaft 300. The shaft 300 pivotally connects and is rotatably carried by links 302 and 304 pivotally connected to the cylindrical boss 274 and the bearing block 286 respectively, as indicated at 306 and 308. At its opposite end, the movable shaft 300 carries a pulley wheel 310 secured thereto and about which is trained a pulley belt 312 which is also trained over a drive pulley 314 carried on the output shaft 316 of the motor 278. The plate 270 is provided with a suitable aperture (not shown) through which the pulley belt 312 extends, and which is shaped to prevent interference with the pulley belt 312 during pivotal movement of the plate 272 relative to the plate 270.

The bearing block 286 and hence the polishing wheel 282 is adjusted vertically by means of the

turnbuckle 294 and is held in desired adjusted position transversely of the conveyor 26 by a rod 318 which is horizontally disposed and one end of which is pivotally connected to the bearing block 286 by the screw 318', as illustrated in Figure 1A, for movement in a horizontal plane. The other end of the rod 318 is externally threaded as indicated at 320 and extends between a pair of fixed angle irons 322 supported on the main frame 20. The threaded portion 320 carries a pair of nuts 324 and co-operating washers 326 which engage the angle irons 322 at opposite sides thereof and which may be adjusted to position the bearing block 286 as desired. It will be appreciated from the foregoing description that the above mentioned pivotal connection of the plate 272 to the plate 270, and the pivotal connection of the rod 318 to the bearing block 286, permit the vertical plane of the polishing wheel 282 to be inclined relative to the conveyor 26 to any desired adjusted position.

A suitable guard housing 328 is carried by the bearing block 286 and partially encloses the polishing wheel 282. The polishing compound and other foreign materials incident to the polishing operation may be carried away through a conduit 330 connected to a suitable exhaust fan (not shown).

In general, it is believed that the operation of the above described polishing machine is apparent from the foregoing description of its construction and accordingly, only a brief statement of the operation will be given herein. Operation of the machine is initiated by placing a quantity of screws, the heads of which are to be polished, in the hopper 22 and turning on the motors 72, 134 and 278. As the hopper 22 rotates in the direction indicated by the arrow in Figure 4, the screws are collected in the slot 52 with the heads supported on the upper surfaces of the annular rings 44 and 46. This collection of the screws in the slot 52 is facilitated by the action of the baffles 54 as above described.

Rotation of the hopper 22 carries the screws disposed in the slot 52 to the fingers 84 which slide under the heads of the screws and lift them from the slot 52. The screws then slide down the strips 74 with the heads supported on the upper portion of the strips 74 and this movement is facilitated by the pneumatic vibrators 88 (see Figure 2). At the lower end of the strips 74, the screws slide onto the transfer plates 234 and 236 from which they are carried away by the conveyor belts 90 and 92 which converge below the transfer plates 234 and 236 to a position in which they grip the shanks of the screws and carry them from the transfer plates 234 and 236 and longitudinally along between the backup members 186 and 188 with their heads supported on the upper surfaces of the conveyor belts 90 and 92. During this movement along the conveyor belts, the screws are carried under the polishing wheels 282 driven by the motor 278. These wheels are adjusted vertically relative to the screws by the turnbuckles 294 and are adjusted so that the polishing wheels are disposed at the desired angle relative to the path of movement of the screws by adjusting the position of the plates 272 on the top plate 270.

After passing the last, or right hand one of the polishing wheels 282, as viewed in Figure 1, the screws are dropped from the conveyor belts 90 and 92 as they diverge from the rollers 264 and 266 toward the pulley wheels 104 and 106 carried on the shafts 96 and 98 at the right hand end

of the machine. The finished screws dropped from the belts 90 and 92 are caught in the slide 268 and slide downwardly into a suitable receptacle (not shown). It will be appreciated that the machine may be adjusted as above indicated to accommodate screws of varying sizes and that the polishing wheels 282 may be turned as desired to insure polishing all portions of the screw heads.

While only one specific embodiment of the invention has been illustrated and described in detail, it will be appreciated by those skilled in the art that numerous modifications and changes may be made without departing from the spirit of the present invention.

What is claimed is:

1. A polishing machine for use in finishing the heads of screws and other like workpieces, said machine comprising a hopper mounted for rotation about an axis inclined to the vertical and having an axially upwardly presenting circular slot communicating with the interior thereof and adapted to collect said screws and a plurality of baffles disposed outwardly of said slot and adapted upon rotation of the hopper with a quantity of screws therein, to carry a number of said screws from the lower portion of said hopper upwardly and cause them to fall toward said slot; a supporting frame; conveyor means mounted on said frame disposed in spaced relation to said hopper and including a pair of continuous belts having portions which extend in parallel relation and have adjacent surfaces disposed in spaced parallel relation adapted to engage the shanks of the screws, said conveyor means including a pair of rollers individual to said belts mounted at corresponding ends of said parallel portions of said belts and supporting said belts at the adjacent sides of said rollers with said surfaces in said spaced parallel relation; a pickup and transfer means for removing said screws from said hopper and delivering them to said conveyor means and including a slide having fingers disposed in said hopper for removing screws from said slot, said slide extending to said conveyor means and being provided with a pair of transfer plates extending between said rollers for transferring said screws from said slide to said belts; polishing means including a polishing wheel disposed above said parallel portions of said belts for polishing the heads of said screws during their movement along said conveyor means and means mounting said polishing means on said frame for adjustment to vary the angle between the plane of said polishing wheel and said parallel portions of said belt; and means connected to said conveyor means for driving each of said belts at a predetermined desired speed independent of the speed of the other of said belts.

2. A polishing machine for use in finishing the heads of screws and other like workpieces, said machine comprising a hopper mounted for rotation about an axis inclined to the vertical and having an axially upwardly presenting circular slot communicating with the interior thereof and adapted to collect said screws and a plurality of baffles disposed outwardly of said slot and adapted upon rotation of the hopper with a quantity of screws therein, to carry a number of said screws from the lower portion of said hopper upwardly and cause them to fall toward said slot; a supporting frame; conveyor means mounted on said frame disposed in spaced relation to said hopper and including a pair of con-

tinuous belts having portions which extend in parallel relation and have adjacent surfaces disposed in spaced parallel relation adapted to engage the shanks of the screws, said conveyor means including a pair of rollers individual to said belts mounted at corresponding ends of said parallel portions of said belts and supporting said belts at the adjacent side of said rollers with said surfaces in said spaced parallel relation; 5 pick up and transfer means for removing said screws from said hopper and delivering them to said conveyor means and including a slide having fingers disposed in said hopper for removing said screws from said slot, said slide extending to said conveyor means and being provided with a pair of transfer plates extending between said rollers for transferring said screws from said slide to said belts; polishing means including a polishing wheel disposed above said parallel portions of said belts for polishing said screws during their movement along said conveyor means, and means operatively connected to said hopper, said polishing means, and said belts for driving said hopper, said polishing means and said belts.

10 20 25 30 35 40 45 50 55 60 65 70 75

3. A hopper for screws and other similarly headed workpieces, said hopper comprising a conical side wall, a bottom disposed in a plane perpendicular to the axis of said conical side wall and including an annular ring extending radially inwardly from said conical side wall at the smaller end thereof toward the axis of said conical side wall and a circular plate concentric with said annular ring and disposed within the central opening defined by said annular ring, said plate having its radially outer edge spaced radially inwardly of the radially inner edge of said ring and co-operating therewith to define an annular slot therebetween communicating with the interior of said hopper and adapted to collect said workpieces therein, means external of said hopper supporting said circular plate disposed as above described, a plurality of baffles mounted on and spaced about the inner side of said conical side wall, said baffles projecting inwardly from and extending generally axially along said side wall.

4. A hopper as defined in claim 3, wherein said baffles terminate at one end adjacent said bottom.

5. A hopper as defined in claim 3, wherein each of said baffles is disposed at an angle relative to the straight line elements of said conical side wall such that upon rotation of the hoppers in one direction, the outer end of each baffle leads the inner with the result that screws engaged by the baffles are urged inwardly toward said bottom.

6. A hopper as defined in claim 3, wherein said ring and said plate carry co-operating annular elements removably secured thereto defining an annular slot therebetween registering with said first named slot, said annular elements being readily replaceable for varying the size of said last named slot.

7. Means for handling screws and other similarly headed workpieces comprising conveyor means including a pair of continuous belts, means supporting said belts with portions extending in parallel relation and with adjacent surfaces of said portions disposed in spaced parallel relation and adapted to engage the shanks of said screws, said last named means including a pair of rollers individual to said belts disposed at corresponding ends of said parallel portions of said belts and supporting said belts at the adjacent

sides of said rollers with said adjacent surfaces of said belts in said spaced parallel relation, said last named means also including a pair of guides spaced from said rollers and spaced from each other a distance greater than the spacing between said rollers so that between said guides and said rollers said belts converge toward said rollers, and means for delivering said screws to said conveyor means and including a slide inclined relative to and downwardly toward said parallel portions of said belts and having a slot adapted to receive the shanks of said screws, said slide being adapted to support said screws with the headed end above said slot, and a pair of transfer plates directly connected to said slide and extending between said rollers for transferring said screws from said slide to said belts.

8. Means for handling screws and other similarly headed workpieces, comprising conveyor means including a pair of continuous belts, means supporting said belts with portions extending in parallel relation and with adjacent surfaces of said portions disposed in spaced parallel relation and adapted to engage the shanks of said screws, said last named means including a pair of rollers individual to said belts disposed at corresponding ends of said parallel portions of said belts and supporting said belts at the adjacent sides of said rollers with said adjacent surfaces of said belts in said spaced parallel relation, said belts converging toward said rollers; a hopper comprising a conical side wall, a bottom disposed in a plane perpendicular to the axis of said conical side wall and including an annular ring extending inwardly from said conical side wall at the smaller end thereof and a circular plate concentric with said annular ring and co-operating therewith to define an annular slot therebetween, means external of said hopper supporting said circular plate disposed as above described, a plurality of baffles mounted on and spaced about the inner side of said conical side wall, said baffles projecting inwardly from and extending generally axially along said side wall; and means for automatically feeding said screws from said hopper to said conveyor means, said last named means including a slide extending from said hopper to said conveyor means and provided with finger means at one end thereof mounted within said hopper adjacent said slot and adapted to transfer said workpieces from said slot to said slide and a pair of transfer plates connected to said slide and projecting between said rollers above said belts for transferring said screws from said slide to said belts.

9. Means for handling screws and other similarly headed workpieces comprising a frame; conveyor means mounted on said frame and including a pair of continuous belts, and means supporting said belts with portions extending in parallel relation and with adjacent surfaces of said portions disposed in spaced parallel relation and adapted to engage the shanks of said screws, said last named means including a pair of rollers individual to said belts disposed at corresponding ends of said parallel portions of said belts and supporting said belts at the adjacent sides of said rollers with said adjacent surfaces of said belts in said spaced parallel relation, said last named means also including a pair of guides spaced from said rollers and spaced from each other a distance greater than the spacing between said rollers so that between said guides and said rollers said belts converge toward said rollers; a slide mounted on said frame adapted to feed

screws to said conveyor means; said slide defining a slot of uniform width inclined relative to and downwardly toward said parallel portions of said belts a pair of transfer plates supported on said frame and disposed generally horizontally and overlying the upper surfaces of said belts, said plates defining a slot therebetween continuous with said slot defined by said slide and being adapted to receive screws from said slide and support them with their heads engaging the adjacent upper surfaces of said plates and their shanks extending downwardly through said slot, said plates being disposed adjacent said rollers so that as said belts converge toward said rollers they are adapted to engage the shanks of screws on said transfer plates and carry them along with the belts.

10. Means for adjustably supporting a wheel for polishing the heads of screws and other like workpieces which are moved horizontally along a conveyor, said means comprising a frame, a supporting member mounted on said frame for pivotal movement relative thereto, a bearing block disposed directly below said member, a shaft journaled in said bearing block and adapted to carry said wheel, means supporting said bearing block on said supporting member in fixed position relative thereto and adjustable for moving said bearing block vertically to selectively move said wheel toward and away from said conveyor, a first link having one end pivotally connected to said bearing block, a second link having one end pivotally connected to said supporting member, a shaft pivotally connecting the other ends of said links and carrying first and second drive pulleys fixed thereto, a third pulley fixed to said first named shaft, a motor mounted on said supporting member having an output shaft and a fourth pulley fixed thereto, an endless belt trained over said first and third pulleys and a second endless belt trained over said second and fourth pulleys, and means adjustably securing said supporting member to said frame whereby said first named shaft may be secured in a desired adjusted horizontal position relative to said conveyor.

11. Means for handling screws as defined in claim 7 and including means operatively connected to said belts for driving said belts with a desired differential between the speeds of said belts.

12. Means for handling screws and other similarly headed workpieces comprising conveyor means including a pair of continuous belts, means supporting said belts with portions extending in parallel relation and with adjacent surfaces of said portions disposed in spaced parallel relation and adapted to engage the shanks of said screws, said last named means including a pair of rollers individual to said belts disposed at corresponding ends of said parallel portions of said belts and supporting said belts at the adjacent sides of said rollers with said adjacent surfaces of said belts in said spaced parallel relation, said belts converging toward said rollers, and means for delivering said screws to said conveyor means and including a slide inclined to the horizontal and having a slot adapted to receive the shanks of said screws and said slide being adapted to support said screws with the headed end above said slot, and a pair of transfer plates connected to said slide and extending between said rollers for transferring said screws from said slide to said belts, said transfer plates overlying said belts and defining a horizontally extending slot there-

between forming a continuation of the slot of said slide and a portion of which extends between said rollers and is aligned with the space adjacent said surfaces of said belts.

13. Means for handling screws and other similarly headed workpieces comprising conveyor means including a pair of continuous belts, means supporting said belts with portions extending in parallel relation and with adjacent surfaces of said portions disposed in spaced parallel relation and adapted to engage the shanks of said screws, said last named means including a pair of rollers individual to said belts disposed at corresponding ends of said parallel portions of said belts and supporting said belts at the adjacent sides of said rollers with said adjacent surfaces of said belts in said spaced parallel relation, said belts converging toward said rollers, and means for delivering said screws to said conveyor means and including a slide inclined to the horizontal and having a slot adapted to receive the shanks of said screws and said slide being adapted to support said screws with the headed end above said slot, and a pair of transfer plates connected to said slide and extending between said rollers for transferring said screws from said slide to said belts, said slide terminating above said belts to prevent interference of said slide with said belts.

14. Means for handling screws and other similarly headed workpieces comprising conveyor means including a pair of continuous belts, means supporting said belts with portions extending in parallel relation and with adjacent surfaces of said portions disposed in spaced parallel relation and adapted to engage the shanks of said screws, said last named means including a pair of rollers individual to said belts disposed at corresponding ends of said parallel portions of said belts and supporting said belts at the adjacent sides of said rollers with said adjacent surfaces of said belts in said spaced parallel relation, said belts converging toward said rollers, and means for delivering said screws to said conveyor means and including a slide inclined to the horizontal and having a slot adapted to receive the shanks of said screws and said slide being adapted to support said screws with the headed end above said slot, and a pair of transfer plates connected to said slide and extending between said rollers for transferring said screws from said slide to said belts, said belts being V-belts and said rollers having their outer surfaces of a configuration adapted to fit the belts and hold them with said adjacent surfaces disposed in said spaced parallel relation.

15. Means for handling screws and other similarly headed workpieces comprising a frame; conveyor means mounted in said frame and including a pair of continuous belts, and means supporting said belts with portions extending in parallel relation and with adjacent surfaces of said portions disposed in spaced parallel relation and adapted to engage the shanks of said screws, said last named means including a pair of rollers individual to said belts disposed at corresponding ends of said parallel portions of said belts and supporting said belts at the adjacent sides of said belts in said spaced parallel relation, said belts converging toward said rollers; a slide mounted on said frame adapted to feed screws to said conveyor means; a pair of transfer plates supported on said frame and disposed generally horizontally and overlying the upper surfaces of said belts, said plates defining a slot therebetween and being adapted to receive screws from said slide and support them with their heads engaging the adjacent upper surfaces of said plates and their shanks extending downwardly through said slot, said plates being disposed adjacent said rollers so that as said belts converge toward said rollers they are adapted to engage the shanks of screws on said transfer plates and carry them along with the belts, the thickness of said plates progressively decreasing in the direction of movement of said belt so that screws carried from said plates by said belts will be disposed with their heads substantially in engagement with the upper surfaces of said belts.

WEBSTER B. KNIGHT.
